UNITED STATES PATENT OFFICE.

ROBERT SCHAELLIBAUM, OF MANCHESTER, ENGLAND.

COTTON-OPENER, &c.

SPECIFICATION forming part of Letters Patent No. 447,365, dated March 3, 1891.

Application filed June 2, 1890. Serial No. 354,027. (No model.) Patented in England June 13, 1885, No. 7,228.

To all whom it may concern:

Be it known that I, ROBERT SCHAELLIBAUM, engineer, a citizen of the Republic of Switzerland, and a resident of Manchester, in the county of Lancaster, Kingdom of Great Britain, have invented new and useful Improvements in Cotton-Openers, Scutchers, &c., Used in the Preparation of Cotton or other Fibers, (for which I have obtained a Patent in Great Britain, No. 7,228, bearing date June 13, 1885,) of which the following is a specification.

My invention relates to improvements in openers, scutchers, &c., used in the preparation of cotton or other fibers, with the exception of what are known as "Crighton openers," and has for its object to make such machines more efficient in opening the cotton or other fibers and extracting impurities therefrom than heretofore has been the case. I attain this by the means illustrated in the accompanying drawings, in which—

Figures 1 and 2 are vertical sections showing my improvements as applied to an opener of the Taylor and Lang system. Figs. 3 and 4 are vertical sections showing my improvements applied to scutchers.

Similar letters refer to similar parts throughout the several views.

In carrying out my invention and when applying the same to all kinds of openers (except Crighton openers) it consists of a stationary comb A in Fig. 1, fixed over the beater or cylinder f in close proximity therewith, in combination with the usual knife-edged grid B. The said comb A is constructed with a metal plate or foundation a, provided with steel pins b and in section generally a parallelogram, the top edge thus forming a knife and acting like the top edges of the usual knife-edged grid-bars g employed in these machines. The pins b, which may be of a round or flat section, are set at such a distance from each other that the largest impurities which generally happen to pass on with the cotton in the respective machines are permitted to pass between the pins b, thus preventing anything from sticking between the pins which would necessitate stripping or cleaning. The pins b are set at an angle to their plate or foundation a with the points thereof and knife-edge of the plate or foundation a inclined against the di-

rection in which the cotton is moving, thus affording the most grip. The points of each longitudinal row of pins b are arranged gradually nearer to the beater or cylinder f than the preceding ones in the direction in which the cotton moves, in order to insure an equal strain on all the rows of pins b. This is attained by either forming each longitudinal row of pins b gradually longer than the preceding one, as shown in Fig. 1, or by forming all of one length and fixing their plate or foundation a at an angle to the beater or cylinder f, as shown in Fig. 2.

When applying my invention to a scutcher, and also to a certain kind of openers, the stationary comb A described is employed in combination with the grid B below the feed-roller, either, as shown in Fig. 3, having teeth growing gradually longer, or, as shown in Fig. 4, having teeth all of one length. The grid B consists of a suitable number of knife-edged metal bars g of the section as illustrated in Figs. 3 and 4, and carried by and arranged to slide in a groove in the bracket h, and kept therein apart from each other by means of blocks h', the stationary comb A being suitably fastened to the bracket h. The inclination of the bars g to the radius of the beater i or cylinder increases from the top to the bottom; and also the distance of the bars g from each other in the same direction for the purpose of obtaining a uniform draft of air through the grid B from the top to the bottom. This combination is intended for scutchers and openers with small porcupines, and for the feeding arrangement of Crighton openers.

What I claim as my invention, and desire to secure by Letters Patent, is—

In an opener or scutcher, the comb A, having a knife-edged plate or foundation a, and pins b, inclined against the direction in which the cotton moves, the points of each longitudinal row of which in the same direction are gradually nearer to the beater or cylinder f than the preceding row, in combination with a knife-edged grid B, substantially as and for the purpose set forth.

ROBERT SCHAELLIBAUM.
